(57) **CLAIM**

The ornamental design for a vaporizer battery, as shown and described.

DESCRIPTION

FIG. 1 is a perspective view of a vaporizer battery, showing my new design;

FIG. 2 is a top plan view thereof;

FIG. 3 is a bottom plan view thereof;

FIG. 4 is a front elevation view thereof;

FIG. 5 is a rear elevation view thereof;

FIG. 6 is a left side elevation view thereof;

FIG. 7 is a right side elevation view thereof; and,

FIG. 8 is a perspective view of the vaporizer battery in a state of use.

The broken lines immediately adjacent the shaded area in FIG. 3 are for the purpose of illustrating a boundary and form no part of the claim. The remaining broken lines are for the purpose of illustrating environmental subject matter and portions of the vaporizer battery that form no part of the claim.
